JOHN FOSTER, OF PAWTUCKET, RHODE ISLAND.

Letters Patent No. 78,273, dated May 26, 1868.

IMPROVEMENT IN MACHINERY FOR PRINTING YARN.

The Schedule referred to in these Letters Patent and making part of the same.

TO ALL WHOM IT MAY CONCERN:

Be it known that I, JOHN FOSTER, of Pawtucket, in the county of Providence, and State of Rhode Island, have invented certain new and useful Improvements in Machines for Printing Yarns; and I do hereby declare that the following specification, taken in connection with the drawings making a part of the same, is a full, clear, and exact description thereof.

Figure 1 shows an enlarged section of the printing-rollers, and an elastic blanket combined therewith.

Figure 2 is a side view of the machine for printing yarn, with the instrument applied.

Figure 3 is a transverse section of the same.

The invention herein described appertains to that class of machines which are used for printing worsted and other yarns in colors. Such machines have long been known and used, both for printing yarns in the hank and by the single thread.

Until a recent date these machines consisted simply of a pair of fluted rollers, each of which was supplied with color from a color-box, in a way well understood among printers. The strands of yarn, being made to travel between the surface of such fluted rollers, and in a line tangential to such surfaces, received an imprint from the ribs of the rollers upon both sides simultaneously, the spaces upon the rollers between the ribs not being filled with coloring-matter, allowing the yarn, in its passage over such spaces, to remain of its natural color.

An improvement in machines of this character is described in the Letters Patent granted to Edward J. Stephens and Hiram E. Green, on the 28th day of August, A. D. 1866, which consists in the substitution of a cylinder with a plain or true surface for one of the fluted rollers previously employed, whereby the injurious effect upon the yarn from the natural cutting-action of a pair of fluted rollers is avoided. While, however, this advantage is gained, an evil of another kind is introduced. The smooth surface of the cylinder, being covered with coloring-matter, smears slightly with color those parts of the yarn which are intended to be left white, and which, in the passage of the yarn through the machine, come over against the spaces between the ribs of the fluted rollers. This smutting of the white portion deprives the yarn, when finished, of the agreeable effect of decided contrast in color which it is the object of the printing process to accomplish.

My invention proposes to furnish a means for retaining the advantages which result from the use of a pair of fluted rollers, without the attendant ill effects which accompany the use of such rollers when, by reason of any want of accuracy in their adjustment to each other, they exert a grinding or cutting-action.

Such invention consists in combining, with a pair of fluted rollers, arranged relatively to each other in the well-known way, an elastic or yielding cushion, which modifies the action of such rollers, and upon which, instead of upon the yarn to be printed, the grinding effect of the rollers is mainly expended.

In the drawings, A A', figs. 1 and 3, represent a pair of fluted rollers, which are geared together, as shown at α α' , fig. 2. They are mounted in bearings, upon a suitable frame, B, in the usual manner. The roller A obtains its coloring-matter from the furnishing-roller, C, which runs in a color-box, D, supplied with the requisite material, in a way familiar to all printers of cloth. This furnishing-roller is driven by the spur-gear wheel b, as shown at fig. 2.

A second color-box is shown at E, fig. 3, and also a second furnishing-roller, F, the effect of which will presently be explained.

The two fluted rollers A A' are placed far enough apart to give room for an endless elastic or yielding apron, G, similar in material and character to a calico-printer's blanket, which passes around one of the fluted rollers, A', and in this instance is arranged to travel over the guiding-rollers H and H', arranged as shown, fig. 3. This blanket or apron, which may be of combined rubber and cloth, or other equivalent material of a yielding character, and possessing elasticity, performs in the machine two functions, one of which is to protect the yarn from injury from the rollers by supplying a yielding cushion, against which the yarn shall bear as it is undergoing the printing process, and which, being interposed between the cutting-edges of the ribs of the printing-rollers, sustains the abrasion which, without this device, would occur to the yarn. The other function which

the apron performs is that of a color-carrier, to enable the ribs of the roller A', which it surrounds, to make, by pressure against it, a print upon the back side of the yarn, simultaneously with the making of the print upon the front side of the yarn by the direct action of the ribs of the roller A.

The apron G is supplied with coloring-matter from the color-box E, by means of the furnishing-roller F, as, from the arrangement shown in the drawing, fig. 3, will be now readily understood.

Motion being given to one of the rollers A. A' by a belt passing around the pulley upon the roller-shaft, the whole train will be put into operation, and the guiding-roller H will be made, through the intermediate gear I, to revolve at the same speed as the printing-rollers, the spur-gear e having the same number of teeth as the gear a'.

The yarn to be printed is conducted from the reel upon which it is wound underneath the roller-beam J, and from thence upward in a straight line, tangential to the surfaces of the printing-rollers, to a convenient point for delivery.

Referring to fig. 1, where an enlarged view of the printing-rollers is shown, the advantage of the endless apron G as a means for adapting a pair of fluted rollers to practical use, and of preserving the advantages which belong to them, is seen. The apron naturally sags into the spaces between the ribs of the roller A', or at least lies in the line of the chord of the arc of the circle described between the edges of the ribs, instead of travelling in the arc of a true circle; consequently the coloring-matter upon such apron will be less likely to smut the portions of the yarn intended to be left white.

What I claim as my invention, and desire to secure by Letters Patent, is—

The combination, with a pair of fluted or grooved rollers A. A', in a machine for printing yarn or other material upon both sides, of an elastic apron, G, or its equivalent, substantially as described for the purposes specified.

JOHN FOSTER.
